CLAIM

I claim the ornamental design for an electric car, as shown and described.

DESCRIPTION

FIG. 1 is a front perspective view of an electric car showing my new design;

FIG. 2 is a rear perspective view thereof;

FIG. 3 is a front view thereof;

FIG. 4 is a side view thereof;

FIG. 5 is a rear view thereof;

FIG. 6 is an opposite side view thereof; and,

FIG. 7 is a top view thereof.

The broken lines shown in the figures illustrate portions of the electric car that form no part of the claimed design.
